E. MAUVAIS

MULTICOPY WRITER

Filed May 6, 1922

UNITED STATES PATENT OFFICE.

ERNEST MAUVAIS, OF SEATTLE, WASHINGTON, ASSIGNOR TO MULTI-COPY WRITER CORPORATION, LTD., OF SEATTLE, WASHINGTON, A CORPORATION OF WASHINGTON.

MULTICOPY WRITER.

Application filed May 6, 1922. Serial No. 558,958.

To all whom it may concern:

Be it known that I, ERNEST MAUVAIS, a citizen of the United States, residing at Seattle, in the county of King and State of Washington, have invented a new and useful Multicopy Writer, of which the following is a specification.

My invention has reference to mechanism whereby one or more duplicate copies of typewriting are made on a typewriter at the same time the original is produced, and without the use of carbon paper; and the objects of my invention are, to provide a device, easily attachable to the carriage of a standard typewriter, carrying a semi-inked typewriter ribbon or a plurality of them, adapted to be instantly adjusted between sheets of paper located in the machine, and opposite the printing point thereof, so that each duplicate is made by a typewriter ribbon; and, to provide effective means for making erasures and correcting mistakes in the original typewriting and a duplicate thereof, without off-setting or making necessary the removal of said sheets from the machine, or the placing of additional sheets of paper therebetween.

In the accompanying drawings—

Figure 1 is a perspective, showing a portion of a typewriter with the device complete, as mounted on the carriage thereof.

Fig. 2, a cross-section drawn on the line 2—2, of Fig. 6.

Fig. 3, a vertical sectional view, on the line 3—3, of Fig. 6.

Fig. 4, a cross-section of a ribbon clip, enlarged and enclosing a section of typewriter ribbon, drawn on the line 4—4, of Fig. 5.

Fig. 5, an elevation of one end post of the device, partly in plan, showing one of the racks extending below the post and outwardly curved, designed to exert tension on the ribbon, a section of which is attached thereto by said clip.

Fig. 6, an end elevation of the device, without its supporting bracket, a section of the post and the gear casing being partly broken away, to show one of the racks and its gear wheel meshing therewith, and including a lower guide bracket for the racks.

Referring more particularly to the drawings; the end posts 1, connected by the transverse piece 2 comprise the frame. 3 and 4 denote gear cases attached thereto, and 5 a

shaft journaled in the oppositely located supports 6. In the present embodiment of the invention these supports are shown attached to the carriage of the typewriter by screws, and not only serve as bearings for said shaft but support the device in operative position on the machine. A lug 7, carrying the screw 8, provides, in connection with one of said supports as shown in Fig. 1, an adjustment whereby the mechanism can be tilted slightly to the required position for operation.

A gear wheel 10, Fig. 3, is fixedly attached to said shaft and is provided with a handle 11 which projects through a slot 12 in the gear casing 3. A second gear wheel 13 is fixedly attached to a sleeve 14 mounted on the shaft 5, and carries a handle 15 which projects through and operates in a semi-circular slot 16 in the gear wheel 10 and the complementary slot 17 in said gear casing. 18 denotes a third gear wheel, likewise attached to a sleeve 19 mounted on the sleeve 14, provided with a handle 20 which projects through semi-circular slots 21 and 22 in gear wheels 10 and 13 and through the slot 23 in the gear casing 3. The gear casing 4, located oppositely of the gear casing 3, encloses three gear wheels each of which is mounted as just described, to the end that a rotation of one of the first mentioned gears 75 by its handle will likewise effect a rotation of a similar gear at the opposite side. The second set of gears are not equipped with handles, and obviously no slots in the gears or said second casing are necessary.

A rack 30 is provided for each gear wheel, adapted to mesh therewith and to slide vertically in a grooved section 31 of the posts 1. In Fig. 5 one of said racks is shown as projecting below the post in which it is 95 mounted. As it will be noted, the lower terminal of the rack is slightly curved outwardly. The racks of one series are thus curved, and the racks of the other series are provided with reversely curved terminals, 100 and as they are all made of material possessing a certain amount of resiliency, a pair of oppositely located and complementary racks when extended below the respective posts in which they operate will each exert 105 a tension outwardly and hold taut a semi-inked typewriter ribbon designed to be mounted between their terminals. While

the tension is sufficient to subserve the purpose mentioned, it still permits a free vertical movement of the rack within said grooved portion of the post. Said ribbon, 5 and connecting clips to be hereafter described, are designed to be of a length short enough to take up the curvatures of the respective racks, and thereby receive a tension that will keep the ribbon taut and operative 10 at all times.

31 denotes a lower guide bracket located adjacent either post and the racks, adapted to assist in maintaining the racks in operative position within the posts. 32 is a slot 15 with which the lower terminal of each rack is provided, for the purpose of receiving a ribbon clip to support a ribbon carried by said terminals. 33, Fig. 6, designates a pair of slight projections on the outer 20 face of each rack between which said clip is located when in operative position, and adapted to limit the movement thereof. As indicated at 34, Fig. 1, an inner side portion of each post is open to permit a free 25 up and down movement of one or more ribbons carried by the several racks.

The ribbon clip 40, shown in enlarged form in Fig. 4, preferably of malleable material, is provided at its looped end with a 30 slot 41, adapted to receive a typewriter ribbon 42. The free ends of the clip terminate, as indicated, in right angular portions 43, and in its medial section it is provided with a reentrant portion 44 and an oppositely located recess 45, complementary thereto. An end of the ribbon is fastened in the clip as shown, in Fig. 4, and the sides of the clip clamped and flattened together, thus securely holding the ribbon. The other end of 40 the ribbon is likewise provided with a clip. A semi-inked ribbon having a clip at either end as described is mounted in the lower terminals of a pair of racks, by inserting a clip in the slot 32 of a rack, as shown in Fig. 45 5, said angular ends holding the clip and attached ribbon against longitudinal movement, and the projections 33, between which the clip is placed, limiting its up and down-movement. The other end of the ribbon is 50 mounted in the opposite and complementary rack in the same way, the resiliency of the racks facilitating the placing of the ribbon, and the curvatures thereof imparting the required tension to the ribbon, as heretofore 55 described.

Sections of semi-inked ribbons having been thus attached to the terminals of the racks, and the device mounted on the carriage of a standard typewriting machine, as 60 indicated in Fig. 1, the mechanism is then ready for operation. It will be noted in Fig. 1 that the handle 11 has been brought forward to the limit of its slot 12. This movement set in motion the gear wheel 10 to 65 which said handle is attached, the shaft 5,

and the complementary gear wheel on the other side of the device and also attached to the shaft. These gear wheels each mesh with a rack on either side, and as is evident, the rotation of the same in a forward direction will lower the ribbon 50, Fig. 1, carried by said racks. The semi-circular slots 12, 17 and 23 are each of a length to bring a ribbon to approximately the printing point when the respective handles are brought forward to the upper limit of the slots. However, should other adjustment be necessary to bring the ribbons, or any of them, in operative position, this can be effected by 70 tilting the frame slightly up or down, 75 through the screw adjustment 8. For purposes of clear illustration, the ribbon of the typewriter is not shown in Fig. 1, but the lowered ribbon 50 indicates its location approximately and is designed to align therewith. The paper fingers of the typewriter are also removed for the same purpose. In using the device, said paper fingers are thrown back, as can be conveniently done on many typewriters of standard make. 51 80 90 95 100 105 110 115 120 125 130 135 140 145 150 155 160 165 170 175 paper the typewriting is practically ruined. The latter method is unsatisfactory on account of the difficulty in so adjusting the sheets of paper, when replaced in the typewriter, as to bring the carbon insertions in proper alignment with the balance of the typewriting. With this device erasures are made by simply turning the sheets forward a few notches of the platen ratchet to get 5 the work to be corrected away from the ribbons and in a convenient place for erasures adjacent the upper portion of the cylinder. Erasures on the original and any duplicate can then be made easily, the cylinder of the 10 typewriter affording a smooth surface for such purpose, with nothing intervening to make a smudge on the sheets of paper. When insertions are to be made, the paper is turned back to the printing point, and as is evident, 15 said insertions will be in perfect alignment, the paper feed and the ratchet end of the cylinder maintaining the several sheets in their original positions.

In the present embodiment of the invention, mechanism is provided for making three duplicate copies. The device is operative with but a single ribbon to make one duplicate copy, and with parts necessary to effect this result. As is evident, by adding 20 similar parts to those already shown, duplicate copies in excess of three can be made at a single writing, if so desired. Preferably, ribbons inked on one side only are used for making said duplicates, to avoid 25 offsetting on the back of preceding sheets, however, sections of the usual typewriter ribbon can be utilized by placing a strip of thin, uninked protecting cloth over the outer face of each ribbon as assembled in the de-

vice, said strips being retained in the clips 40 in the same manner as said ribbon is held.

Other changes in and modifications of the construction described may be made without departing from the spirit of my invention, or sacrificing its advantages, and hence I 45 ask that I be not confined to the specific structure set forth.

I claim:

1. A device of the class described, comprising a frame attachable to the carriage 50 of a typewriter, a pair of oppositely disposed racks mounted in the frame and slideable vertically therein, a gear wheel adapted to mesh with each rack, a shaft connecting the gear wheels, a second pair of oppositely 55 disposed racks mounted in the frame and slideable vertically therein, a gear wheel adapted to mesh with each of the second racks, a sleeve mounted on the shaft and connecting the second gear wheels, a typewriter ribbon disposed between the lower ends of each pair of said racks, and means for imparting a rotary movement to said 60 wheels, shaft and sleeve and a vertical movement to said racks, whereby each ribbon may 65 be lowered to the printing point of the typewriter or raised therefrom independently of the other ribbon.

2. In a device of the class described, a pair of supports adapted to be attached to 70 either end of a typewriter carriage, a frame, a shaft carried thereby and journaled in the supports, a lug connected with the frame, and a screw threaded in the lug and contacting with one of the supports adjacent 75 thereto whereby the frame may be tilted.

ERNEST MAUVAIS.
